2,049,142

PLATE STRAIGHTENING MACHINE

Fritz Ungerer, Pforzheim, Germany

Application August 31, 1934, Serial No. 742,265
In Germany September 14, 1933

REISSUED

5 Claims. (Cl. 153—54)

This invention relates to an adjustable supporting device for the straightening rolls of plate straightening machines, in which the adjusting means for the supporting rollers provided along 5 the straightening rolls for deflecting these rolls towards or away from the material to be straightened can travel into the supporting position along paths of different lengths.

The invention relates to a supporting device 10 of this type but with the improvement that the adjusting means for the supporting rollers can be brought into the supporting position separately and independently from other existing rollers whilst the machine is running, and that 15 further the supporting of the row of straightening rolls to be deflected is effected not only by a single pair of rows of supporting rollers arranged symmetrically to the middle of the straightening rolls but by more than two rows 20 of supporting rollers situated as close as possible side by side along the row of straightening rolls.

By the invention it is possible, without interruption of service, to act on the straightening 25 rolls at more points than heretofore and to any desired degree so that the shape of these rolls can be much better adapted to the straightening requirements of the individual plates.

Two embodiments of the invention are illustrated by way of example in the accompanying 30 drawings in which:—

Fig. 1 shows in front elevation a plate straightening machine with supporting rollers adjustable in rows.

Fig. 2 shows in front elevation a row of supporting rollers according to the first form of construction, with adjusting means.

Fig. 3 is a side elevation of Fig. 2.

Fig. 4 is a diagrammatic view showing the effect of the adjusting means of the first form of construction.

Fig. 5 shows in front elevation a straightening machine with supporting rollers adapted to be adjusted in rows at an angle.

Fig. 6 is a top plan view of the adjusting means of the second form of construction.

Fig. 7 shows in front elevation a bearing member for the supporting rollers with adjusting means.

Fig. 8 is a side elevation of Fig. 7.

Fig. 9 is a cross section through the straightening rolls with supporting rollers and

Fig. 10 is a diagrammatic view showing the effect of the adjusting means of the second form 55 of construction.

Fig. 11 shows in side elevation a row of supporting rollers divided into sections with separate adjusting means for each section.

Uprights *a* are mounted on a box base *a* and upper and lower straightening rolls *b* are journaled in these uprights. These rolls are supported by supporting rollers *c* and *d*, the upper rollers *c* being carried in known manner in a yoke member not shown in the drawings, so that they participate in the adjusting movements of the member, whereas the lower rollers *d* are mounted in rows in bearing members *e* resting on slide surfaces of the bearing feet *e* (Figs. 2 and 7). These bearing feet are mounted directly on screw spindles *f*, which can be turned 10 by means of worm gearings *g*, *g*₁ in the nuts *h* supported on the box base *a*. The worm gearings *g*, *g*₁ are driven by means of a shaft *o* which is rotated by a hand wheel *o*. Each worm gearing *g*, *g*₁ can be coupled with the driving shaft *o* 15 independently of the others. For this purpose a system of levers *k*, *m*, *n* is provided for engaging and disengaging claw clutches *i*. According to the direction in which the shaft *o* rotates the screw spindles *f* coupled therewith are screwed 20 into or out of the nuts *h* and consequently the bearing feet *e* and bearing members *e* are lowered or raised.

In the example illustrated in Figs. 1 to 4 the lowering or raising of a bearing foot *e* causes at 25 the same time a horizontal lowering or raising of a whole row of supporting rollers on every bearing foot *e*, as the bearing members *e* of the same row of supporting rollers rest. The effect of this form of construction is therefore that any 30 desired row of supporting rollers can be raised or lowered any desired distance independently of the other rows of supporting rollers by engaging its associate clutch *i*. Thus, for example in the diagram of Fig. 4, the first and fifth rows 40 of supporting rollers, counted from the hand wheel side of the machine are raised relative to the remaining rows of supporting rollers, resulting in a deflection of the row of straightening rolls in the shape indicated in an exaggerated 45 manner.

In the form of construction illustrated in Figs. 5 to 10 the raising and lowering of a bearing foot *e* does not cause a horizontal but a one sided lowering or raising of one of the two outer or of the 50 two inner rows of supporting rollers, as two bearing members *e* of two adjacent rows of supporting rollers always rest on the inner bearing feet *e*. It is therefore possible, to adjust in roof-shape or in pattern shape every two adjacent rows of 55

supporting rollers relative to the rows of straightening rolls. Thus, for example in the diagram shown in Fig. 10, the outer pairs of supporting rollers are always adjusted in roof shape, thus causing during the straightening of a plate a stretching of two lateral longitudinal sections. The clutch controlling mechanism *k* for coupling the adjusting means *j* separately or jointly with the common hand wheel shaft *o* for these means is advantageously arranged laterally on the machine frame *a*, *a*₁ preferably near the handle *o*₁ of the shaft *o*.

It is not necessary to act with one and the same adjusting means upon a whole row of supporting rollers but the rows of supporting rollers may be subdivided and the parts thereof supported individually by separate adjusting means as shown in Fig. 11.

I claim:—

20 1. An adjustable supporting device for the straightening rolls of plate straightening machines, in which the adjusting means for the supporting rollers arranged for the purpose of flexing towards or away from the material to be straightened, along the straightening rolls, can move into the supporting position along paths of different length, comprising in combination with the rows of supporting rollers and the rows of straightening rolls, means for adjusting some of

25 these supporting rollers during the service and without interrupting the passage of the plates separately and independently of the other supporting rollers, the supporting of the row of straightening rolls to be flexed being effected by more than two rows of supporting rollers situated close together.

30 2. An adjustable supporting device for the straightening rolls of plate straightening machines, in which the adjusting means for the sup-

40 porting rollers arranged for the purpose of flexing towards or away from the material to be straightened, along the straightening rolls, can move into the supporting position along paths of different length, comprising in combination with

45 the rows of supporting rollers and the rows of straightening rolls, means for adjusting some of these supporting rollers during the service and without interrupting the passage of the plates separately and independently of the means for

50 adjusting the other supporting rollers, the supporting of the row of straightening rolls to be flexed being effected by more than two rows of supporting rollers situated close together, each of the several rows of supporting rollers arranged 55 side by side along a row of straightening rolls being separately raised and lowered any desired distance relative to its associate row of straightening rolls.

3. An adjustable supporting device for the straightening rolls of plate straightening machines, in which the adjusting means for the supporting rollers arranged for the purpose of flexing towards or away from the material to be straightened, along the straightening rolls, can 60 move into the supporting position along paths of different length, comprising in combination with the rows of supporting rollers and the rows of

straightening rolls, means for adjusting some of these supporting rollers during the service and without interrupting the passage of the plates separately and independently of the means for adjusting the other supporting rollers, the supporting of the row of straightening rolls to be flexed being effected by more than two rows of supporting rollers situated close together every two adjacent rows of supporting rollers of the several rows of supporting rollers situated side 10 by side along a row of straightening rolls being adjusted in roof-shape and in gutter shape relative to its row of straightening rolls.

4. An adjustable supporting device for the straightening rolls of plate straightening ma- 15 chines, in which the adjusting means for the supporting rollers arranged for the purpose of flexing towards or away from the material to be straightened, along the straightening rolls, can move into the supporting position along paths of 20 different length, comprising in combination with the rows of supporting rollers and the rows of straightening rolls, means for adjusting some of these supporting rollers during the service and without interrupting the passage of the plates 25 separately and independently of the means for adjusting the other supporting rollers, the supporting of the row of straightening rolls to be flexed being effected by more than two rows of supporting rollers situated close together, a com- 30 mon shaft for the adjusting means, a hand wheel on said shaft at the side of said machine frame, and means for coupling said adjusting means individually and jointly with said shaft arranged laterally on said machine frame preferably near 35 said hand wheel.

5. An adjustable supporting device for the straightening rolls of plate straightening machines, in which the adjusting means for the sup- 40 porting rollers arranged for the purpose of flex- 45 ing towards or away from the material to be straightened along the straightening rolls, can move into the supporting position along paths of different length, comprising in combination with the rows of supporting rollers and the rows of straightening rolls, means for adjusting some 50 of these supporting rollers during the service and without interrupting the passage of the plates separately and independently of the means for adjusting the other supporting rollers, the sup-

55 porting of the row of straightening rolls to be flexed being effected by more than two rows of supporting rollers situated close together, in combination with the machine frame, a common shaft for the adjusting means, a hand wheel on said shaft at the side of said machine frame, and means for coupling said adjusting means individually or jointly with said shaft arranged laterally on said machine frame preferably near 60 said hand wheel, the adjusting means comprising screw spindles, worm gears adapted to transmit the movement of said common shaft to said screw spindles, claw clutches between said worm gears and said shaft, and a system of levers adapted to engage and disengage said claw clutch to connect said worm gears with said shaft.

FRITZ UNGERER.
